UNITED STATES PATENT OFFICE.

JOSEPH L. WRIGHT, OF CLEVELAND, OHIO, ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,330,226.

Specification of Letters Patent. Patented Feb. 10, 1920.

Application filed October 21, 1915. Serial No. 57,055.

To all whom it may concern:

Be it known that I, JOSEPH L. WRIGHT, a citizen of the United States, residing at Cleveland, in the county of Cuyahoga and 5 State of Ohio, have invented certain new and useful Improvements in Telephone-Exchange Systems, of which the following is a specification.

My invention relates to telephone exchange systems. The object of my invention is to produce a system requiring a minimum amount of apparatus of the simplest type for effecting connections between lines of calling and called subscribers.

10 Another object of my invention is to provide quick and efficient method of operation.

The operators at the central station are provided with answering and calling sets of 20 keys, used for controlling the interconnection of subscribers' lines. These keys take the place of the ordinary plugs and cords used in so-called manual exchanges. The operator is provided with a number of sets of answering and calling key-sets to enable 25 her to handle the originating calls without loss of time.

In addition to the key-sets the operator is provided with a group or bank of signal lamps, one being individual to each line appropriated to her position.

30 In the so-called semi-automatic systems the operator is usually provided with a sending device for controlling step-by-step switching mechanism for extending connections from calling to called subscribers' lines.

With my invention the cords or plugs of the so-called manual systems are dispensed with, as well as the step-by-step mechanism 40 and sending devices used in semi-automatic systems.

Each set of answering and calling keys is provided with a set of what are termed "tens-relays." Each tens-relay of a set 45 preferably contains the terminals of ten subscribers' lines. By providing ten relays for each set, access is given to one-hundred lines. Opposite sets of contacts in these relays are connected to contacts in what are 50 termed "units-keys." These contacts are multiplied into each tens-relay of its set. The tens-relays are controlled by a separate set of tens-keys or buttons. In order to operate a particular tens-relay a correspond-

ing tens-button is depressed thereby energizing the selected relay.

The particular units-button is then depressed, which connects the link or trunk to the selected line through the contacts of the operated tens-relay and contacts of the 60 units-button.

The grouping of tens-relays and units-relays are fully disclosed in Patent No. 1,091,193, to E. E. Clement, March 24, 1914. I dispense entirely with the use of the units-relays, however, by substituting units-keys 65 or buttons.

As each end of the link or connecting circuit is provided with a set of tens and units-buttons and co-operating tens-relays, the operator by depressing the proper buttons can interconnect any line over the link circuit.

Provision is made to provide automatic, disconnect or release of the buttons when either the calling or called subscribers hang 75 up their receivers, thus dispensing with supervision by the operator.

My invention is illustrated in the accompanying drawings, wherein:

Figure 1 shows a calling subscriber's line 80 equipment, a set of answering buttons and co-operating relays.

Fig. 2 shows a link or connecting circuit.

Fig. 3 shows the equipment of a called subscriber's line equipment, a set of calling buttons and co-operating relays.

Referring to Fig. 1, the subscriber's equipment at A comprises apparatus usual in common battery systems. The line wires terminate in a line relay D through the contacts 90 of a cut-off relay C. The set of tens-buttons are shown at T and a set of units-buttons at U. These buttons or keys are of the usual locking and indicating type. When a button in one row is depressed it will release the 95 button formerly depressed. Each strip of keys is provided with a release magnet which, upon operating, moves the latch, thereby causing the automatic restoration of the keys. Keys operated in this manner are 100 old in the art and need not be described.

I have shown by five tens-relays of the set, each one being equipped with but two sets of contacts. There are three contacts in each set, as I have illustrated, what is termed 105 a three-conductor circuit.

A complete set of relays would comprise ten relays, each one equipped with thirty

contacts. Contacts which engage corresponding contacts leading to the lines are multiplied as shown. The first set of these contacts of each relay are connected in multiple and also connected to contacts in No. 1 unit-button. No. 2 set of contacts in each relay are connected in multiple and also connected to contacts in No. 2 unit-button. This manner of connecting the buttons and contacts of the relays is continued throughout the set.

In case each operator is provided with ten sets of answering and calling buttons, then the line contacts of the tens-relays will be multiplied as disclosed in the Clement Patent No. 1,091,193. The line contacts of the answering relays in the present instance will also be connected in multiple to contacts of the tens calling relays so as to enable the operator to effect connection with any line through the calling set of relays, shown in Fig. 3.

Each line relay D will control an individual signal lamp O. If the lines are formed into groups of one-hundred, then there will be one-hundred of these signal lamps before the operator.

Referring to Fig. 2, the tip and sleeve conductors 4-6, 22-24 are separated by 30 the condensers 5 and 23 as shown.

The tip conductor 4, sleeve conductor 22 and conductor 33 are connected to contacts in each of the units buttons in the row V. Battery supply is furnished to the calling 35 subscriber through the windings of relay F and retardation coil S.

Battery supply is furnished the called subscriber through the windings of relay H and retardation coil V.

40 Relay J is the ringing relay controlled by the constantly rotating commutator W. K is the test relay for determining the condition of the called line.

The equipment illustrated in Fig. 3 is 45 identical with that of Fig. 1 and need not be described. The unit set of buttons UU is, however, provided with a set of contacts indicated at X (Fig. 2). The contacts X are closed when any one of the units buttons 50 is depressed to its extreme or near extreme position. These contacts may be controlled by the latch bar common to all the keys in the strip. When pressure is removed from the button the contacts separate and assume 55 the position shown in Fig. 2. These contacts are utilized for applying the test relay to the called line in order to determine whether it is busy or idle.

The operation of the system is as follows: 60 The subscriber at A removing his receiver causes the operation of relay D which in turn completes the circuit of the signal lamp O. For illustration we will assume that the number of the calling line is 22; the operator upon noticing the illumination of lamp

No. 22, depresses No. 2 button in the row T and No. 2 button in the row U. The operation of No. 2 button in the row T completes the circuit of the tens-relay 20 thereby connecting the ten lines in the group 70 containing the calling line to the multiplied contacts leading to the contacts in the buttons U. As button No. 2 in the row U is depressed it follows that only one of the ten lines will be connected, namely; line No. 75 22. The operation of relay 20 and button No. 2 in the row U places relays E and C in series. The operation of relay C disconnects relay D, thereby extinguishing the signal lamp O. The tip relay F is energized 80 through the subscriber's telephone set.

The operator then depresses the answering button 100 and connects her telephone set directly across the tip and sleeve conductors allowing her to converse with the calling subscriber.

The operator upon learning the number desired, which we will assume to be 111, depresses No. 1 button in the row TT, and No. 1 button in the row UU. The operation of the button TT operates relay 110, thereby connecting the group of ten lines containing the called line to the contacts of the buttons UU. As No. 1 button is depressed it, therefore, follows that only one 95 line, namely, 111, will be connected to the called end of the link or connecting circuit (Fig. 2).

In depressing the button in the unit row UU the contacts springs X are closed thereby operating relay L. The operation of this relay disconnects battery from the winding of relay H and ground from the winding of relay V, and also disconnects relay I from conductor 51, and in its place 105 connects the test relay K. This conductor 51 extends to the winding of the cut-off relay of the called line, and if the called line is busy battery will be connected to conductor 51 through the winding of some other 110 relay I. If the called line tests busy, relay K will become operated and complete the circuit of release magnets MM and NN of the tens and units keys in multiple by the following path: ground, contacts of relay 115 K, 39, windings of magnets MM and NN to battery B. The operation of these magnets cause the restoration of No. 1 keys in the tens and units rows. The restoration of these keys indicates to the operator that the 120 called line is busy. The operation of relay K also connects the busy tone signal to the sleeve conductor 36, which notifies the calling subscriber that the called-for line is busy. Relay K when operated is kept 125 locked to battery through the contacts of relay F controlled by the calling subscriber. The calling subscriber upon replacing his receiver after receiving the busy indication causes the deenergization of relay F. This 130

relay in restoring unlocks relay K and completes the circuit of the release magnets M and N of the keys U and T in multiple by the following path: ground, contacts of relay E, 35, contacts of relay F, 36, winding of magnets M and N to battery B. The operation of these magnets causes the restoration of the depressed buttons in their respective rows. The restoration of the buttons causes the release of relay 20 and of relays C and E.

In case the called-for line is not busy, then relay I will be placed in series with the cut-off relay of the called line. The operation of the cut-off relay disconnects its associated line relay and connects the line conductors to the line extensions leading to the contacts in relay 110. The operation of relay I completes the circuit of relay J by the following path: ground, commutator W, winding of relay J, 45, contacts of relay I, 44, to battery B through the contacts of relay G. The operation of relay J is intermittent and when energized applies ringing current from generator R to the called line.

When the called subscriber removes his receiver during a non-ringing interval the relay H is operated thereby completing the circuit of relay G by the following path: ground, contacts of relay H, winding of relay G, 43, contacts of relay I to battery B. The operation of relay G prevents the operation of relay J and also places the control of the release magnet MM and NN under control of the called subscriber. The relay G is provided with a locking contact and after being operated by relay H is thereafter under control of relay I.

At the termination of the conversation the calling subscriber replacing his receiver causes the deenergization of relay F thereby causing the restoration of the buttons in the rows T and U in the manner previously described.

The called subscriber replacing his receiver causes the deenergization of relay H, which in restoring completes the circuit of magnets MM and NN by the following path: ground, contacts of relay H, 41, contacts of relay G, 38, contacts of relay K, 39, windings of magnets MM and NN to battery B. The operation of these magnets causes the restoration of the keys TT and UU. The restoration of the key TT releases relay 110, and also severs the connection between relay I and the cut-off relay of the called line. Relay I restoring removes battery from the winding of relay G thereby causing it to restore.

In case the called-for subscriber does not answer then the calling subscriber controls the release of the buttons UU and TT by energizing magnets MM and NN in multiple by the following path: ground, contacts of relay E, 35, contacts of relay F, 36, 37,

contacts of relay G, 38, contacts of relay K, 39, windings of magnets MM and NN to battery B. The operation of these magnets causes the restoration of the keys in the rows TT and UU and the operation of the magnets M and N in the rows T and U in the manner previously described causing the restoration of the keys depressed in these rows.

From the foregoing description it will be noted that the duties of the operator are very simple, as it is only necessary for her to note the position or number of the signal lamp and then depress the answering button corresponding to the number indicated and then after ascertaining the number desired depress corresponding calling buttons. After once establishing a connection there is no necessity for supervision, as the calling and called subscriber are automatically released upon the replacing of their receivers.

While I have illustrated but one operator's connecting trunk or link circuit, each end provided with a set of keys, it naturally follows that each operator will be provided with enough connecting circuits to care for the traffic at her position.

I preferably arrange a group of one-hundred line signals at each operator's position and in case there are several hundred lines terminating in the exchange to which access must be given through the calling end of the trunk it is necessary to provide extra sets of tens or hundreds keys or buttons. For each one-hundred lines there will be ten buttons, as shown at TT controlling ten relays.

In case there are three-hundred lines in the exchange then each outgoing or calling end of the trunk will be provided with thirty buttons TT and thirty relays controlled thereby. The units keys UU will be multiplied into corresponding contacts of the thirty relays. Of course the line contacts of the three-hundred lines will be multiplied into each set of relays at every operator's position which is controlled by the buttons TT.

The only multiplied connections extending from one connecting trunk to another are the line contacts of the called lines.

In case the rows of buttons TT are arranged side by side then each one of the three rows can be provided with a resetting button which serves to trip the latch and release the buttons in its particular row. Each row may be provided with eleven buttons, the extra button simply serving to restore any of the other buttons in the row but having no connections to the control relays.

While I have shown a release magnet individual to each row of buttons UU and TT a single release magnet can be provided to release the latches of both rows.

In place of using rows of buttons a rotating switch may be provided. This switch can be rotated by the operator to the proper position and tripped by a release magnet 5 to restore it to its normal position or supervisory signals may be associated with the connecting links as in the ordinary manual systems.

With this arrangement the operator can 10 control the release of the switches or buttons at will.

Having thus described my invention, what I desire to secure by Letters Patent is:

1. In a telephone exchange system, the 15 combination with calling and called subscribers' lines, of a link circuit, a set of relays and keys individual to said link for connecting a calling line to said link, and a corresponding set of relays and keys for also 20 connecting a called line to said link, said relays and keys serving as a sole means for connecting said line and link circuit.

2. In a telephone exchange system, the 25 combination with calling and called subscribers' lines, of a link circuit, a set of relays and keys individual to the answering end of said link, and a corresponding set of relays and keys individual to the calling end of said link, means for operating said relays 30 and keys for connecting a calling line to the answering end of the link and for connecting a called line to the calling end of said link for conversational purposes, said relays and keys serving as a sole means for inter- 35 connecting said line with said link circuit.

3. In a telephone exchange system, the 40 combination with a plurality of subscribers' lines, of a link circuit, a set of tens-relays and a set of coöperating units-keys associated with each end of said link circuit, means for operating said keys and relays for interconnecting said lines.

4. In a telephone exchange system, the 45 combination with a plurality of electrical circuits, of a link circuit, a set of relays and a set of coöperating keys individual to each end of said link circuit, means for operating said keys and relays for interconnecting said electrical circuits over said link circuit, said relays and keys serving as a sole means 50 for interconnecting said electrical circuits over said link circuit.

5. In a telephone exchange system, the 55 combination with a calling and a called subscriber's line, of a link circuit, a set of co-operating relays and keys associated with the answering end of said link, and a corresponding set of coöperating relays and keys associated with the calling end of said link, 60 restoring means for each set of keys, means for operating said relays and keys for connecting a calling line to the answering end of the link and for connecting a called line to the calling end of the link, means controlled by the calling and called lines for op-

erating the respective releasing means for said keys.

6. In a telephone exchange system, the 70 combination with calling and called subscribers' lines, of a link circuit, a set of relays and two sets of keys associated with the answering end of said link, and a corresponding set of relays and keys associated with the calling end of said link, means controlled by one set of keys for operating the 75 relays and means controlled by the other set of keys and contacts of said relays for connecting the calling line to the answering end of the link, and for connecting the called line to the calling end of said link. 80

7. In a telephone exchange system, the 85 combination with a called subscriber's line, of a link circuit, a set of relays and keys associated with said link, means for operating said relays and keys for connecting said line to said link, additional means associated directly with said keys for determining whether the called line is busy or idle.

8. In a telephone exchange system, the 90 combination with a plurality of subscribers' lines, of a link circuit, a set of relays and two sets of keys associated with said link, means controlled by one set of keys for operating said relays, means controlled by the other set of keys for connecting said link to 95 any one of said lines, said connection extending through the contacts of the other said set of keys.

9. In a telephone exchange system, the 100 combination with a plurality of subscribers' lines, of a link circuit, a set of relays and keys associated with said link, means controlled by some of the keys for operating said relays, and means controlled through the contacts of other of said keys and contacts of said operated relays for connecting any line to said link, the connection of said line when completed extending through the contacts of said relays and keys. 105

10. In a telephone exchange system, the 110 combination with a plurality of subscribers' lines, of a link circuit provided with a set of relays and keys, some of the keys having contacts connected to said link and other contacts connected to contacts in said relays, 115 said relays being provided with coöperating contacts connected to said lines, means controlled by the other of said keys for operating said relays to connect said lines to said link, the connection of said lines to said link 120 extending through the contacts of said relays and keys.

11. In a telephone exchange system, the 125 combination with a plurality of subscribers' lines, of a link circuit provided with a set of relays and keys individual to said link circuit, the contacts of said relays being connected to said lines and to contacts of said keys, means for operating said relays and said keys for connecting said lines to said 130

link, said lines when connected to said link extending directly through the contacts of said relays and said keys.

12. In a telephone exchange system, the combination with a called subscriber's line, of a link circuit, a set of relays and keys associated with said link for effecting connection with said lines, of a test relay associated with said link, means associated with 5 said keys when connection is effected with said line for directly connecting said test relay thereto for determining whether the said line is busy or idle.

13. In a telephone exchange system, the combination with a called subscriber's line, of a link circuit, a set of relays and keys associated with said link for effecting connection with said lines, of a test relay associated with said link, means associated with 15 said keys when connection is effected with said lines for connecting said test relay thereto for determining whether the called line is busy or idle, releasing means for said keys, means controlled by said relay for 20 effecting said releasing means.

14. In a telephone exchange system, the combination with a called subscriber's line, of a link circuit for interconnecting with said line, a set of keys associated with said 25 link provided with an auxiliary set of contacts, means controlled through said contacts when interconnecting said link with said line for determining whether the line is busy or idle.

- 30 15. In a telephone exchange system, the combination of a plurality of subscribers' lines, of signals individual to said lines, a link circuit common to said lines, a set of relays and a set of coöperating keys associated with 35 said link circuit for directly interconnecting with any of said lines in response to said signals, releasing means for said keys and relays, said releasing means being controlled by said lines.

- 40 16. In a telephone exchange system, the combination of a plurality of subscribers' lines, a link circuit, a set of relays and a set of coöperating keys individual to each end of said link circuit, means for operating said 45 keys and relays for interconnecting said lines.

- 50 17. In a telephone exchange system, the combination of calling and called subscribers' lines, of a link circuit, a set of relays and keys individual to the answering end of said link, a corresponding set of relays and keys individual to the calling end of said link, means controlled by one of said keys for operating the relays to connect the calling lines to one end of said link and means controlled by the other set of keys for operating the other set of relays for connecting the called lines to the opposite end of the link.

- 55 18. In a telephone exchange system, the

combination of a called subscriber's line, of a link circuit, a set of relays and keys associated with said link for effecting connection with said line, a test relay associated with said link, releasing means for said keys, 70 means associated with said keys when connection is effected with busy lines for operating said test relay for rendering operable said releasing means.

19. In a telephone exchange system, the combination of a plurality of subscribers' lines, of a link circuit, a set of relays and a set of coöperating keys associated with each 75 end of said link circuit, means for operating said keys and relays for interconnecting said lines, and means controlled over said lines after interconnection for releasing said keys and relays.

20. In a telephone exchange system, the combination of a plurality of subscribers' 80 lines, of a signal individual to each of said lines, a plurality of link circuits, a set of relays and a set of coöperating keys associated with said link circuit located at an operator's position, means controlled by said operator 85 for connecting any one of said lines in response to said signals to any one of said link circuits, signals for said link circuits, said signals serving to indicate the condition of the connection when established.

21. In a telephone exchange system, the combination of a plurality of subscribers' lines, of a plurality of link circuits, a set of relays and coöperating keys associated with each end of said link circuit, an operator's 90 position, means controlled from said position for operating said keys and relays of any one of said link circuits for interconnecting said lines.

22. In a telephone exchange system, the combination of a plurality of subscribers' lines, of a plurality of link circuits, a set of relays and coöperating keys associated with each end of said link circuit, an operator's 105 position, means controlled from said position for operating said keys and relays of any one of said link circuits for interconnecting said lines, releasing means for said keys and relays, said releasing means controlled by said lines after interconnection.

23. In a telephone exchange system, the combination of a plurality of subscribers' lines, a link circuit, a set of keys associated with each end of said link circuit, means controlled by said keys for interconnecting 110 said lines over said link circuit.

24. In a telephone exchange system, the combination with a plurality of subscribers' lines, a link circuit, a set of relays and a set of coöperating keys individual to each 125 end of said link circuit, means controlled by said relays for interconnecting said lines over said link circuit.

25. In a telephone exchange system, the combination of a plurality of electrical cir- 130

cuits, a link circuit, a set of relays and a set of coöperating keys individual to each end of said link circuit, means controlled by said relays for interconnecting said electrical circuits over said link circuit.

26. In a telephone exchange system, the combination of a plurality of electrical circuits, a link circuit, a set of relays and a set of coöperating keys individual to each end of said link circuit, means controlled by said relays for interconnecting said electrical

circuits over said link circuit, a signal for said link circuit, said signal serving to indicate the condition of the electrical circuits when so interconnected. 15

In testimony whereof I affix my signature in the presence of two witnesses.

JOSEPH L. WRIGHT.
